FLUORESCENT LIGHT FIXTURE

Edward F. Zurawski, Chicago, Ill., assignor to Garey Corporation, a corporation of Illinois

Filed July 10, 1958, Ser. No. 51,723

Term of patent 14 years

(Cl. D48—23)

Fig. 1

Fig. 2

Fig. 3

Fig. 5

Fig. 4

FIGURE 1 is a perspective view of a fluorescent light fixture showing my new design;

FIG. 2 is a bottom plan view thereof;

FIG. 3 is a side elevational view thereof;

FIG. 4 is an end elevational view of the fixture taken from the opposite end of FIG. 1; and

FIG. 5 is an enlarged fragmentary sectional view taken substantially on line 5—5 of FIG. 1.

I claim:

The ornamental design for a fluorescent light fixture, substantially as shown.
